UNITED STATES PATENT OFFICE.

JAMES I. JONES, OF WASHINGTON, DISTRICT OF COLUMBIA, ASSIGNOR OF ONE-HALF
TO RACHEL R. BROWNE, OF WASHINGTON, DISTRICT OF COLUMBIA.

CONCRETE-MOLD.

1,397,253.

Specification of Letters Patent. Patented Nov. 15, 1921.

Application filed August 16, 1921. Serial No. 492,663.

To all whom it may concern:

Be it known that I, JAMES I. JONES, a citizen of the United States, residing at Washington, in the District of Columbia, have invented certain new and useful Improvements in Concrete-Molds, of which the following is a full, clear, and exact description.

This invention relates to structures for molding concrete, cement, and the like, and has for its object to provide such a structure with means for suspending the side plates and thereby avoid the use of a base member.

15 A further object of the invention is to provide such a molding structure that the upper surface of the concrete will be spaced from the molding apparatus in order that such surface may be troweled or finished 20 while the apparatus remains in its original position.

Another object of the invention is to provide a mold which may be used for laying either curved or straight curbing.

25 Other objects and advantages of the invention will be apparent from the following description when taken in connection with the accompanying drawing, in which—

Figure 1 is a transverse section through 30 the apparatus.

Fig. 2 is a longitudinal section there-
through.

Fig. 3 is a detail section showing a portion of the mold removed.

35 Fig. 4 is a plan view.

Fig. 5 is a section through a slightly modified form.

Fig. 6 is a section through another modification; and,

40 Fig. 7 is a detail plan view of an improved brace member.

Referring to the drawing more in detail, and particularly to Figs. 1 to 4, inclusive, the supports comprise the stakes 1 and horizontal brace members 2. Connected to the 45 brace members 2 and depending therefrom are a plurality of hangers 3. The hangers 3 are arranged in pairs and may be clamped against outward movement by means of the bolts 4 located adjacent the top and bottom of the brace member 2. Side plates 5 are secured to the hangers 3 and have attached to their outer faces the horizontally disposed reinforcing members or plates 6. Brackets 7 may be interposed between the

side plates 5 and the reinforcing members 6.

In operation, the apparatus is arranged as shown in Figs. 1 and 2, and the concrete is poured in the usual manner. By having the side plates suspended as shown, it is 60 unnecessary to provide a base for these plates, such however, is almost always necessary when using the old method, especially when working in soft or muddy ground.

As shown in Fig. 3 of the drawing, a 65 side plate may be removed by merely loosening the bolts 4 and removing the nails passing into the brace member 2; the face of the curb or other part being formed is then free to be finished in any manner desired. 70 In order to retain the remaining plate in position I provide the stake 8.

In Fig. 5 is shown an apparatus for molding wall copings. In this form of the invention the supports including the stakes 1 and 75 braces 2 are dispensed with, and the hangers 3 are clamped to the wall by means of the bolts 4.

Fig. 6 shows a structure for molding a combined curb and gutter, and is substantially the same as the construction shown in Figs. 1 to 4 inclusive with the exception that the side plate 5' is somewhat shorter than plate 5 so as to provide space for the gutter. Furthermore, a secondary plate 5" 85 is supported in position by means of the stakes 1', to form the edge of the gutter.

In Fig. 7 I have shown a form of reinforcing member 6', which may be used either for forming curves or for straight work as 90 may be desired. To this end the plate is provided with a curved edge and a straight edge. This plate may be supported from the hangers 3 with its curved edge facing inwardly or may be reversed if straight 95 curbing is to be laid.

In accordance with the patent statutes I have described what I now believe to be the best embodiment of the invention, but I do not wish to be understood thereby as 100 limiting myself or the scope of the invention, as many changes and modifications may be made without departing from the spirit of the invention, all such I aim to include in the scope of the appended claims. 105

What I claim as new and desire to secure by Letters Patent is:

1. A concrete mold including a plurality of stakes, transverse brace members connecting pairs of stakes, hangers rigidly con- 110

nected with and depending from said brace members, and side plates connected to said hangers.

2. A concrete mold including a support, 5 hangers depending therefrom, side plates secured to said hangers, and one or more bolts connecting said hangers.

3. A concrete mold including a support, side plates connected therewith, and reinforcing members connected to said plates, 10 said reinforcing members having a straight edge and a curved edge.

JAMES I. JONES.
